ELECTRIC PLUG CONNECTER

Estel C. Raney, Columbus, Ohio

Application September 26, 1929
Serial No. 395,416

2 Claims. (Cl. 173—328)

5 My invention has for its object to provide an efficient electric connector. Connecters containing the invention are particularly of value where gasses or materials exist that are deleterious to the metal contacts of the electric circuit connector or where inflammable gasses or vapors may become ignited by the break in the circuit at the contacts when disconnection is made.

10 Preferred forms or embodiments of the invention utilize terminals that are frictionally and elastically engaged by spring contacts that are enclosed in a substantially sealed chamber which prevents the entrance of injurious or inflammable gases or vapors in advance of the separation of 15 the contacts and terminals. The invention also provides an efficient female plug that may be used for a great variety of purposes.

15 The invention may be contained in connectors that vary in their details of construction and, to 20 illustrate a practical application of the invention, I have selected a plug connector containing the invention as an example of the various forms of structure that embody the invention, and shall describe the connector hereinafter. The connector selected for purposes of illustration is 25 shown in the accompanying drawing.

Fig. 1 is a side view of the connector, a part 30 being shown in section. Fig. 2 is a view of a partitioning plate that divides the female member of the connector into a chamber for containing the terminals and a socket for receiving the member that is connected through the connector. Fig. 3 is an end view of one of the parts of the connector looking up, the partitioning plate having 35 been removed therefrom. Fig. 4 is a view of a section taken on the plane of the line 4—4 indicated in Fig. 3, the relative dimensions, however, being larger than those of Fig. 3. Fig. 5 is a view of a section, taken on the plane of the 40 lines 5—5 indicated in Fig. 1. Fig. 6 is a view of a section taken on the plane of the line 6—6 indicated in Fig. 3. Fig. 7 is a partial cross-sectional view of the contacts of the connector 45 illustrating the means by which the contacts are maintained in a closed position relative to one another. Fig. 8 is a perspective view in elevation of the male member of the connector. Fig. 9 is a view of a section taken on the plane of line 50 9—9 indicated in Fig. 2. Fig. 10 illustrates a view in perspective of one of the interior parts of the connector.

55 In the form of construction selected as an example of the embodiments of my invention, a female plug is provided for connecting a thermally operated switch with an external circuit, the

switch being particularly adapted for use in connection with refrigerating apparatus. The connector provides a means for making ready connection with the thermic device through the contacts which are enclosed within a shell and sealed as against the admission of a gas. As shown in the figures, the end portions 1 of the terminals 2 that protrude from an end wall of the thermic device 3, are bent substantially at right angles to the body portions of the terminals so as to extend in opposite directions, and a female member having contacts 4, located in a closed chamber 5 that is formed within the shell 6 of the member by means of a partitioning plate 7, is used for connecting an external circuit with the terminals 2.

60 The shell 6 of the female member is preferably formed of insulating material and is provided with a skirt portion 10 having a shoulder 11. The plate 7 fits the interior of the skirt portion 65 of the shell and is set against the shoulder 11 and forms, thereby, the chamber 5 and the socket 12. The terminals of the external circuit, or contacts of the connector, are located within the chamber 5. The socket 12 is formed to fit 70 against, or around, an end part of the device 3. Thus, the lower edge portion of the skirt 10 is so formed as to fit about the end part 13 of the thermic switch 3 and against the rim portion 85 of the end of the thermic device.

75 The contacts 4 are secured by means of a pair of bushings 15 that are embedded in the insulating material that forms the shell. The ends of the contacts are provided with openings and are placed so as to surround the ends of the bushings 15. The ends of the bushings are flanged over the edge portion of the contacts about the openings. If desired, the contacts may be provided with ears 17 that may be struck up therefrom to confine the wire of the external circuit 90 to which the connector is connected. The bushings 15 are threaded, and threaded sleeves 20 are inserted in the bushings. The sleeves 20 have flanges 21 at their outer ends and, in order that they may be screwed into the bushing, the outer ends of the sleeves may be provided with notches or slots 22 to receive a screw driver. Thus, the ends of the connecting wires 23 may be placed 95 around the outer ends of the sleeves 20 and the sleeves 20 may be threaded into the bushings 15 to clamp the ends of the wires.

100 The sleeves 20 are also provided with female threads and the plate 7 may be secured in position against the shoulder 11 by means of the 110

screws 24 that may be passed through the plate 7 and screwed into the sleeves.

The plate 7 is provided with a pair of radially extending openings 25 and arcuate slots 26 that are located from the center of the plate substantially the same distance that the terminals 2 are located from the center of the device 3. The arcuate slots 26 communicate with the radially extending openings 25. The openings 25 have a size substantially the same as the bent end portions 1 of the terminals 2. Consequently, the terminals 2 may be inserted through the openings 25 and then turned so that the body portions of the terminals 2 are moved in the arcuate slots 26. The ends of the contacts 4 being located contiguous to the openings 25, they will be engaged by the end portions 1 of the terminals 2.

The contacts 4 slope from the bottom of the shell and terminate in the vicinity to the side edges of the radially extending openings 25 of the plate. Preferably, they are inclined to the plate so that the ends engage the surface of the plate 7 and when the plate 7 is secured in position, the springs will be slightly pressed, whereby the ends of the contacts 4 will be yielding held against the surface of the plate. Preferably, the plate 7 is provided with recessed portions 28 that extends to the edges of the openings 25 and so as to locate edge portions of the bottoms of the recesses 28 at the openings 25 and within the surface of the body of the plate. The ends of the contacts lie in the recesses. When the terminals 2 are inserted into the chamber 5 through the openings 25, and the end part 13 of the thermic device 3 is located in the socket 12, the right angularly extending portions 1 of the terminals 2 will be located at a point within the inner surface of the plate 7 about the thickness of the contacts 4. The ends of the contacts that lie in the recesses 28, will be located well below the angularly extending portions 1 so that when the thermic device 3 is rotated and the terminals 2 move in the slots 26, the right angular extending portions 1 will move over the surfaces of the contacts 4. Since the contacts 4 incline away from the inner surface of the plate 7 they will frictionally and elastically resist such movement, and by their elasticity will operate to draw the thermic device 3 tightly in the socket 12 and produce a pressure between the upper end of the thermic device 3 and the edge of the skirt 10.

Preferably, the contacts are provided with punched out points 30, and the portions 1 of the terminals 2 are provided with openings 31 that register with the raised portions 30 of the contacts 4. The raised portions 30 are so located that on the completion of the rotative movement of the thermic device 3 as provided for by the slots 28, the punched out portions 30 will enter the open-

ings 31 to secure with a still greater frictional resistance the shell 6 relative to the thermic device 3 and prevent disconnection between the contacts and the terminals.

The end wall of the shell 6 is provided with an opening 35 and the wires 23 of the external circuit are enclosed in, preferably, a flexible insulating covering 36 that tightly fits the opening 35. This seals the interior of the chamber of the shell. Preferably, a collar 37 is secured to the inner end of the insulating covering 36 to prevent withdrawal of the wires from the shell 6 and also prevent a direct pull of the ends of the wire 23 from the binding posts formed by the bushings 15 and the sleeves 20.

I claim:

1. A plug connector comprising a shell having a wall, the wall having a pair of openings and surfaces inclined to the inside surface of the wall to form depressions on the inside side of the wall and extending to and having their greater depth at the openings, arcuate shaped spring contacts located on the inside of the wall and terminating at the openings and having end portions located in the depressions formed by the said inclined surfaces and bowed away from the inclined surfaces and the adjoining surface of the body of the wall, the other end portions of the contacts connected to the wall, a member having a pair of terminals, the terminals having turned ends insertible through and rotatable in the openings, the terminals protruding from the member a length to cause the turned ends to engage and ride the inside sides of the spring contacts when the member is rotated to increase the contact pressure between the terminals and the contacts and securely hold the member against the outside surface of the wall.

2. A plug connector comprising a shell having a wall forming a chamber within the shell, the wall having radially extending openings, a pair of arcuate shaped contacts located in the chamber, one end of each of the contacts secured to the wall and the other end slidably located on the surface of the wall and terminating near the edge of the opening and having a portion intermediate its ends raised above the surface of the wall, a member having a pair of terminals, the terminals having parts extending at right angles to body parts of the terminals and insertible through the opening in the wall, the radially extending terminal parts located from the member a distance to enable insertion of the radially extending terminal parts through the wall and the engagement of the inner surfaces of the contacts remote from the end edges of the contacts when rotated and the member is placed against the shell and operable to depress the raised central portions of the contacts and press the member against the shell.

ESTEL C. RANEY. 135
